RECIPROCATING PUMP

Kenelm Edward Lee Guinness, London, England

Application December 7, 1931, Serial No. 579,388
In Great Britain December 23, 1930

2 Claims. (Cl. 128—257)

This invention is for improvements in or relating to reciprocating pumps and one of the objects of the invention is to provide a simplified reciprocating pump in which no outlet valve is required. Another object of the invention is to provide improved means for controlling the rate of discharge of liquid from a reciprocating pump without materially affecting the pressure in the outlet conduit.

Another object of the invention is the provision of dental-operating or massaging appliance whereby a pulsating jet of liquid, such as dentifrice or mouth wash, may be directed into the mouth of a patient or on to other parts of the body. Another object of this invention is to provide a construction of apparatus for producing such a pulsating jet which shall be efficient and simple to operate.

According to one feature of the invention a pump comprises a cylinder, means for reciprocating a piston at high frequency therein and an outlet conduit of narrow bore in permanent communication with the cylinder. The purpose of constructing the outlet conduit of narrow bore is to produce a high velocity and therefore a high kinetic energy in the liquid as it is discharged from the pump cylinder. The kinetic energy of the liquid and, to a certain extent, the friction between the liquid and the conduit prevent the liquid from returning to the cylinder during the return stroke of the piston. A pump constructed in this way gives a pulsating jet of liquid which is found to be more efficient than an even jet for many purposes such as, for example, car washing. A pulsating jet is also advantageous for cleaning the teeth, also massaging and other surgical or hygienic operations.

Another object of the invention is to provide an improved construction of regulating valve; other objects of the invention will appear hereinafter.

Particular forms of construction of reciprocating pump according to the present invention will now be described by way of example with reference to the accompanying drawings, of which:

Figure 1 is a side sectional elevation of a complete dental-operating apparatus incorporating a pump according to the invention;

Figure 2 is a sectional plan on line 2—2 of Figure 1;

Figure 3 is a side sectional elevation of the regulating valve on the line 3—3 of Figure 1; while

Figure 4 is an enlarged sectional plan view on the line 4—4 of Figure 3, of the regulating valve.

As shown in Figures 1 and 2, the appliance

comprises a base 10 of synthetic resin or other insulating material on which is attached a disc-shaped block 11 of the same material by means of bolts or screws 12. The block 11 supports an electric motor 13, only the casing and terminals 5 of which are shown. The casing 13 of the motor is surmounted by another insulating block 15, also of synthetic resin or other insulating material, and affixed to the block 15 is a push-switch of any known construction comprising 10 a casing 16 and a push-button 17. The push-switch and electric motor are enclosed by a metal casing comprising a crown portion 18 and a cylindrical portion 19. The cylindrical portion 19 is 15 slidable through a short distance on the peripheries of the insulating blocks 11 and 15 and is constrained by pins 20 screwed in the block 11 and engaging slots 21 in the casing 19. The casing 18, 19 is normally held in its uppermost position, as shown, by the spring or the equivalent 20 normally comprised in the push-switch 16.

The base 10 is cut with a cylindrical recess 73 which receives a correspondingly-shaped portion of the block 11 and with a cylindrical hole 22 which accommodates the mechanism now to be 25 described.

The shaft 23 of the electric motor 13 terminates in a boss 24, carrying an eccentric pin 25. The pin 25 has mounted on it two bushes 26 of insulating material which engage a metal ring 27 30 between them; the bushes 26 and the ring 27 are held together and in tight engagement with the pin 25 by a nut 28 and washer 29 at the end of the pin.

The base 10 is bored with a radial hole 30 to 35 accommodate a piston 31 which is guided in a tube 32, the tube 32 being held in position by a metal nose 33 secured to the base 10 by studs 34. The piston 31 is a tube closed at both ends and having narrow circumferential grooves 35 on 40 its outer surface which prevent leakage of fluid in known manner. At its end the piston 31 is furnished with a head 36 which abuts the metal ring 27. Between the head 36 and the outer end of the hole 30 is a compression spring 37 which 45 keeps the head in engagement with the ring. In the outer end of the nose 33 is fitted a tube 38, leaving a gap between it and the tube 32. The inner end 39 of the tube 38 receives the outer end 50 of the piston 31 and is hereinafter referred to as the cylinder. In a preferred construction, the piston, when at the end of its return stroke is 0.02 of an inch outside the cylinder 39. The tube 38 contains a bush 40 held in by a milled nut 41. The bush 40 receives the end of a length of flexi- 55

ble metal tubing 43 and is also fitted internally with a narrow metal tube 42 which projects some distance into the flexible tubing 43.

In the wall of the nose 33 opposite the end of the piston 31 is a horizontal inlet tube 44 to which is attached a length of rubber tubing 45 having a weighted end 46. On the same transverse axis of the nose 33, a vertical tube 47 enters and carries a rubber bulb 48 affixed to its upper end. On the left hand side, in Figure 1, of the hole 22 in the base 10, there is another radial hole 49 which receives a tightly fitting plug 50 of felt by which the ring 27 is lubricated. An oil hole 51 which is closed by a cap 52 is provided in the base 10 for admitting oil to the plug 50.

The flexible metal or armoured tubing 43 is about 4 feet long and is covered throughout by a rubber sheath being as non-resilient as is practicable. At its far end it enters the handle of the appliance which comprises a cylindrical metal grip 53 having a hole at one end through which the tubing 43 enters and a screwed-in bush 54 at the other end. At the inner end of the bush 54 there is fixed in a connecting tube 55 to which is attached one end of a short length of rubber-canvas tubing 56, the other end of which engages and is bound round the end of the flexible tubing 43. The bush 54 also receives a tapering metal tube 57 which is rotatable within it and is separated from the connecting tube 55 by flexible washers or other packing 58. The outer end of the tube 57 is screwed to the body 59 of a regulating valve which will now be described.

As shown now in Figures 1, 3 and 4, the regulating valve comprises a body 59 in the form of a stepped tube, one limb of which contains the inlet port 60 and the other the outlet port 61. The body has a vertical tapering hole which receives a barrel 62 which is provided with a cross-piece 63 for a handle. The barrel has two circumferential grooves 64 and 65 which register with the ports 60 and 61 respectively. The groove 64 is of varying depth and as can be seen more clearly from Figure 4, the cross-section of the barrel at that point is an eccentric circle tangential to the hole in the body so that the groove varies from maximum depth on one side to nothing on the opposite side. The groove 65 is of uniform depth all round. The grooves 64 and 65 are interconnected by a short longitudinal groove 66. The barrel 62 is held in the body 59 by means of a nut 67 and washer 68. The action of the regulating valve is described hereinafter.

The outlet side of the body 59 receives a gland nut 69 which holds in a rubber or other packing-ring 70. A suitably curved metal tube 71 is sweated in the nut to communicate with the outlet port 61 and a nozzle 72 is sweated to the other end of the tube 71.

The appliance is used on the teeth as follows: the weighted end 46 of the rubber tubing 45 is lowered into a receptacle, for example a jug, of liquid dentifrice or mouth-wash, and the rubber bulb 48 is squeezed and then released. This has the effect of expelling the air from the bulb and sucking in the liquid to the region of the cylinder 39. With one hand, the handle 53 is held so that nozzle 72 is in a suitable position for directing the jet of liquid into the mouth. The other hand is rested on the crown 18 of the motor casing. The weight of the hand depresses the casing and the push-button 17, whereupon the motor starts up, the shaft 23 and eccentric pin

25 rotate and the piston 31 is reciprocated. The forward motion of the piston 31 is provided by the ring 27 while the return motion is effected by the spring 37. At each forward stroke of the piston the liquid in the cylinder 39 is forced through the tube 42 along the tube 43, through the tube 53 and, by way of regulating valve 59, out of the nozzle 72. The bore of the tube 42, the stroke of the piston 31 and the speed of the motor 13 are so correlated that there is substantially no return of liquid to the cylinder 39 during the return stroke of the piston 31. The return stroke of the piston and the speed of the outgoing liquid produces a vacuum in the cylinder 39 until the piston leaves the cylinder, whereupon fresh liquid is sucked in through the annular space to be discharged through the tube 42 during the next forward stroke of the piston. The length and bore of the tube 42 are of considerable importance because it is the narrowness of this tube compared with the swept volume of the pump which gives the desired vacuum in the cylinder 39. The pressure head produced in the cylinder is converted partially into velocity head as the liquid passes through the tube 42 and this velocity gives the liquid its necessary kinetic energy to prevent it from returning to the cylinder during the return stroke of the piston.

It has been found in practice that suitable figures are as follows.—

Speed of motor—3,300 R. P. M.

Diameter of tube 42—.067 bore

Length of tube 42—4½ inches

Diameter of tube 43— $\frac{1}{8}$ bore

Length of tube 43—4 feet

Stroke of piston— $\frac{1}{8}$ inch

Distance from cylinder 39 of piston at the end of its return stroke—.02

Diameter of piston— $\frac{1}{4}$ inch

With the motor running, the liquid is discharged from the nozzle 72 in high-speed pulsations. While it is desirable that the jet should pulsate, it is found advantageous to damp out the peaks of pressure to a certain extent and that is the reason for providing the canvas-rubber tube 56 which, by its resilient expansibility partially absorbs the pressure fluctuations without completely destroying them.

As the pin 25 and the ring 27 rotate, the ring 27 bears against the felt plug 50 and thus the line of contact between the ring 27 and the head 36 is kept lubricated.

The regulating valve 59 works as follows: When the barrel is in the angular position shown in Figure 4, the widest part of the groove 64 is in register with the inlet port 60 so that liquid passes relatively freely from the inlet port 60 into the groove 64, down along the groove 66, into the groove 65 and out through the outlet port 61 to the tube 71. However, as the arm 63 is rotated, the width of the groove 64 lying adjacent to the inlet port 60 is gradually diminished (in whichever direction the barrel is rotated) and thus the quantity and pressure of liquid discharged from the nozzle 72 are gradually diminished. Finally, when the barrel has been turned through 180°, the inlet port is completely blocked and the discharge of liquid completely cut off. In these conditions, there is no outlet for the liquid pumped into the tubing 43 but the tube is so constructed that it is sufficiently extensible to accommodate the pulsations and thus prevent the apparatus from bursting. In some cases, the extensibility of the armoured

pipe 43 is sufficient, alone, to damp out the high peaks of pressure satisfactorily, in which case the canvas rubber tubing 56 may be dispensed with.

5 It will be seen that the apparatus described above provides an effective means for applying a pulsating jet of liquid to the teeth or gums of a patient or for any other massaging purposes and is simple to manipulate. The tapering tube 57 is rotatable in the bush 54 so that the regulating valve 59, tube 71 and nozzle 72 may be rotated to any desired position independently of the handle 53. The use of the insulating blocks 11 and 15, the insulating base 15 10 and the insulating bushes 26 makes for safety and prevents any electric current from finding its way from the motor windings or connections to the handle or nozzle 72.

It will also be seen that a regulating valve 20 according to the invention has the great advantage over known constructions that there is a large angular movement of the barrel between the extreme "on" and "off" positions of the valve, and the valve is therefore very sensitive. In the 25 construction illustrated, this angular movement is substantially 180°. In an alternative construction, the groove-base may be shaped like a snail cam in which case the angular movement is substantially 360°.

30 It will be appreciated that other prime-movers than the electric motor may be used, for example, a water turbine.

In a modification of the present invention the apparatus may be so connected up to a source 35 of electric current that a current flows along the jet of discharged liquid and gives an additional stimulating effect to the parts to be treated. For example, when the apparatus is used as a dental-operating apparatus, the circuit may be 40 through the liquid, from the jet to the mouth or gums of the patient and through the body of the patient to earth.

Although it is preferred to use a flexible metal tube for connecting the pump to the jet, it will be appreciated that a reinforced rubber or other tube could be used. The flexible metal tube is preferred on account of the fact that it responds less to the pulsations produced in the column of liquid which it conducts to the jet and hence increases the pulsating effect at the jet. It will be seen that the pump produces a jet of medicated liquid which may be projected against the teeth or gums or dental interspaces with a high frequency impulse action. The effect of the action on the teeth is to dislodge particles of food or organisms and the effect on the gums is to massage them beneficially.

It will also be seen that the invention makes possible a far simpler construction of reciprocating pump than hitherto. If the sizes are suitably chosen, the pump can be used for almost any purpose to which reciprocating pumps are ordinarily put.

It will be understood that the details of construction in the specific examples herein described may be varied within wide limits and still lie within the scope of the invention.

I claim:—

1. A massaging device comprising a nozzle adapted to effect a jet discharge, a reciprocating liquid supply pump, and means for actuating the pump at a sufficiently high speed and short stroke 30 to substantially prevent back flow of the liquid on the back stroke of the pump.

2. A massaging device comprising a high speed reciprocating short stroke liquid supply pump, a nozzle adapted to effect a jet discharge, and 35 a conduit connecting said pump and said nozzle, said conduit having means therein for damping without destroying the pulsations of the discharge liquid.

KENELM EDWARD LEE GUINNESS. 40
